SIGNALING DEVICE FOR VEHICLES

Filed Aug. 31, 1928

THOMAS NAYLOR.
INVENTOR.

BY Harold C. Shigman
ATTORNEY

UNITED STATES PATENT OFFICE

THOMAS NAYLOR, OF EDMONTON, ALBERTA, CANADA

SIGNALING DEVICE FOR VEHICLES

Application filed August 31, 1928, Serial No. 303,267, and in Canada August 23, 1928.

This invention relates to a signaling device for vehicles and the main object is to provide a simple construction, yet one which will accomplish the desired result in the most efficient manner.

With the foregoing and other objects in view, as will appear as the description proceeds, the invention consists of the novel construction, combination and arrangement of co-operating elements as hereinafter more specifically set forth, claimed and shown in the accompanying drawing forming a part of the present application, in which:

Fig. 1 is a front plan view of a portion of an automobile, showing in full lines the preferred embodiment of my invention, while, in dotted lines, I show the safety arm in operative position.

Fig. 2 is an enlarged sectional view showing the detail construction of my invention, parts being broken away.

Fig. 3 is a modified form of my invention, adapting it for accommodation of a signal, illuminated by electricity.

Like numerals of reference designate corresponding parts throughout the different views.

4 indicates a vehicle which, in the particular illustration shown, is the front portion of a closed type automobile, which is provided with a top 5, a corner post 6 and facer board 7. Extending through the facer board adjacent one end, I provide a bearing member 8. This bearing member may be of any desired style, which may be tightly clamped into position in the opening formed to receive the same in the facer board 7. 9 is a shaft, having a squared inner end portion 10 and a squared outer end portion 11. Fitted on the squared portion 10, I provide an operating arm 12, the outer free end of which has attached thereto a connecting member 14. This connecting member is provided with a ring 15 and a further connecting member 16, which connects into a ring 17, the purpose of which will be hereinafter mentioned.

18 is the signaling arm having an offset portion 19, which portion is provided with a squared opening adapted to fit over the squared portion 11 and retained thereon by

the nut 20. This arm 18 is provided with an indicator reflector 21. 23 is a stop block fitted on the corner post 6 into which the lower portion of the arm 18 swings when in inoperative position.

When travelling along the road and desirous to turn to the left, a signal is required to the traffic coming after. This signaling device is most efficient in giving this required signal. When in inoperative position, the ring 17 is engaged on the hook 22. When it is desired to signal that the vehicle is about to be turned to the left, the ring 15 is pulled down and engaged on the hook 22. The pulling down of this ring 15 and its connection through the member 14, arm 12 and shaft 9, causes the arm 18 to be swung to an approximate right angle direction outwardly from the corner post 6. The operator, in the vehicle coming after the vehicle to which the signaling device is attached, will readily see the indication given that the operator is to make a left hand turn.

On vehicles other than automobiles provided with a tail light, certain Provinces in Canada and certain States in the United States require that illuminated signaling devices be attached thereto. To provide a construction adapted for this purpose, I provide a casing 24 threadedly engaged on a signaling arm 18^a, which arm has therein suitable electric wire connections 25 to a light 26 in the casing 24. The casing may be provided with a frosted lens in the front and a red coloured lens in the rear or any other combination to comply with the requirements of the Province or State in which it is to be used. The ends of the wires 25 may be connected to any suitable source of supply, for example a storage battery placed in any suitable position in the vehicle. The other parts and operation of the signal will be the same as hereinbefore described.

The foregoing specification and annexed drawing disclose the preferred embodiment of my invention, but it is to be understood that minor changes may be resorted to in the commercial adaptation of my invention without departing from the scope of the invention as hereinafter claimed.

What I claim as new is:

A signaling device for vehicles comprising a sleeve bearing fixedly supported through the facer board of said vehicle inwardly of the corner post thereof; a shaft rotatably mounted through said sleeve; a signaling arm fixedly connected to the outer end of said shaft; an operating arm fixedly connected to the inner end of said shaft; a pull member, having one end secured to said operating arm; a hook on the corner post of said vehicle to which said pull member is adapted to be attached; said signaling arm having the greater portion thereof in offset alignment to the under portion connected with said shaft, so that the major portion of said operating arm will lie adjacent in front of and in parallel alignment with the corner post of said vehicle and a stop means carried on said post.

In testimony whereof, I affix my signature.

THOMAS NAYLOR.
